UNITED STATES PATENT OFFICE.

ALBERT MERFEY ALEXANDER, OF VALLEY MILLS, TEXAS.

FOOT ACCELERATOR.

Application filed December 29, 1921. Serial No. 525,644.

To all whom it may concern:

Be it known that I, ALBERT M. ALEXANDER, a citizen of the United States, and resident of Valley Mills, in the county of Bosque and State of Texas, have invented certain new and useful Improvements in Foot Accelerators, of which the following is a specification.

This invention relates to accelerators especially adapted for use on automobiles.

An important object of the invention is to provide a foot accelerator which may be conveniently applied to a motor vehicle without substantially altering the construction of the vehicle and without marring the appearance of the same.

Further the invention forming the subject matter of this application is provided with novel means whereby the same may be employed for actuating the throttle arm of the carbureter without interfering with the hand operated throttle.

A further object of the invention is to provide a foot accelerator which is of highly simplified construction, durable in use and cheap to manufacture.

Other objects and advantages of the invention will be apparent during the course of the following description.

In the accompanying drawing forming a part of this application and in which like numerals are employed to designate like parts throughout the same,

Figure 1 is a perspective of the improved accelerator applied.

Figure 2 is a perspective of a bracket embodied in the invention.

Figure 3 is a perspective of a throttle operating rod embodied in the invention.

In the drawing wherein for the purpose of illustration is shown the preferred embodiment of the invention the numeral 5 designates a vehicle frame to which the engine 6 is bolted in the usual manner. As illustrated in Figure 1 the carbureter 8 is connected to the engine by means of the intake manifold 9 and is provided with a throttle arm 10 normally operated by the transversely extending link 11. The transversely extending link 11 which is connected to the throttle arm 10 is operated by means of the usual hand throttle arranged adjacent the steering wheel of the vehicle.

The invention forming the subject matter of this application includes a longitudinally movable arm 14 having its rear portion

curved longitudinally as indicated at 15 and terminating in an ear 16 apertured for the reception of a pivot element 17 by means of which the arm is connected to a pedal 18. The pedal 18 is in the nature of a longitudinally movable rod having its forward portion provided with a pair of spaced parallel ears 20 connected to the apertured ear 16 by means of the pivot element 17. 65

As illustrated in Figure 1 the movable pedal 18 is slidable through the foot board of the vehicle and is provided with a disk-shaped head 22 adapted to be depressed by the foot when it is desired to operate the throttle arm 10 of the carbureter. A suitable rest 24 may be secured to the foot board of the motor vehicle adjacent the head 22 and may support a suitable portion of one's foot so that the plunger or rod 18 may be conveniently depressed. 75

The intermediate portion of the arm 14 is offset laterally as indicated at 25 and the bend in the offset portion is apertured as indicated at 26 for the reception of one end 80 of a coiled spring 27. The coiled spring is connected at its rear end to a suitable stationary portion of the engine and serves as a means for urging the throttle valve to its closed position. However, when the pedal is depressed the spring yields and permits the arm 14 to move forwardly. 85

The forward portion of the arm 14 is provided with a bend defining a laterally projecting attaching member 29 adapted for 90 connection with the throttle arm of the carbureter. The arm rearwardly of the laterally projecting attaching member 29 is arranged in L-shaped formation to provide an upwardly extending branch 30 with a forwardly extending branch 31, which overhangs the carbureter. The spring 27 pulls rearwardly and is arranged directly behind the L-shaped member defined by the branches 30 and 31 so that as soon as the foot is released the attaching member will be drawn rearwardly. 100

The longitudinally curved arm 15 is slid able through the horizontally arranged loop 35 of a bracket generally designated by the numeral 36, the said bracket being formed from a single length of metal having one end portion apertured as indicated at 37 for the reception of fastening devices whereby the bracket may be firmly secured to the frame 105 of the vehicle or to any other convenient place. The intermediate portion of the 110

length of metal from which the bracket is formed is provided with a clip 38 defining an upstanding arm 39 from which the elongated loop 35 extends. As illustrated in 5 Figure 2 is a pair of pulleys 40 are arranged within the loop and serve as a means for guiding the arm or curved portion. When the throttle arm 10 is moved about the axis of the butterfly a limited lateral movement 10 of the arm 14 takes place and as the pulleys or guide rollers 40 are arranged in spaced relation this lateral movement of the arm is permitted.

In operation the pedal 18 is depressed for 15 advancing the arm 14 and this advancement of the arm results in the operation of the throttle 10. When the pedal 18 is released the spring 27 promptly returns the arm 14 to its original position for cutting off the 20 flow of fuel.

Also an accelerator constructed in accordance with this invention may be conveniently applied to any vehicle without altering the construction of the same and by reason of 25 the construction employed the parts are not easily rendered inoperative.

Having thus described the invention, what is claimed is:—

1. A foot accelerator for motor vehicles 30 comprising an arm having its forward portion provided with means whereby the same may be connected to the throttle arm of the carbureter, said arm being provided intermediate its ends with an offset portion, a 35 coiled spring connected to said offset portion and forming a means for retracting said arm, a longitudinally movable pedal pivotally connected to the rear portion of said arm, and a bracket having a loop and a 40 pair of guide wheels contacting with the rear portion of said arm.

2. A foot accelerator for motor vehicles

comprising an arm having its intermediate portion offset laterally, and its forward portion arranged in L-shaped formation to provide upwardly and forwardly extending branches, the forwardly extending branch being adapted to overhang the throttle arm of the carbureter, said forwardly extending branch being provided with means whereby the same may be pivotally connected to the throttle arm of the carbureter, the rear portion of said arm being curved longitudinally and provided with an apertured ear, a longitudinally movable pedal slidable 55 through the floor board of the vehicle and having its forward portion connected to the apertured ear of the arm and having its rear portion provided with a head adapted to be depressed by one's foot, a bracket formed from a length of metal having an attaching base and a horizontally arranged elongated loop, said loop being provided with a pair of spaced guide wheels between which the rear portion of said arm moves, and spring 60 means connected to said arm for retracting the same.

3. A foot accelerator comprising an arm having its intermediate portion offset and its forward portion arranged in L-shaped 70 formation to provide upwardly and forwardly extending branches, the forwardly extending branch being adapted to overhang the throttle arm of the carbureter, said forwardly extending branch being provided 75 with means whereby the same may be pivotally connected to the throttle arm of the carbureter, the rear portion of said arm being curved longitudinally and provided with an apertured ear, and a longitudinally movable pedal slidable through the floor board of the vehicle and having its forward portion connected to the apertured ear.

ALBERT MERFEY ALEXANDER.
